ATTACHMENT FOR SINK FAUCETS

Filed Feb. 12, 1925

Inventor

Oavis H. Vallier

By Harry D. Wallace
Attorney

UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

ATTACHMENT FOR SINK FAUCETS.

Application filed February 12, 1925. Serial No. 8,783.

To all whom it may concern:

Be it known that I, ORVIS W. VALLIER, a citizen of the United States, residing at Watertown, in the county of Jefferson and 5 State of New York, have invented certain new and useful Improvements in Attachments for Sink Faucets, of which the following is a specification.

This invention relates to a novel form of 10 soap holder for use with sinks and relates more particularly to means for supporting the soap holder above the water valve controlling handle and in back thereof and more specifically to support the soap holder from 15 the valve casing.

Figure 1 is a front elevation of an ordinary kitchen sink. Fig. 2 is a view partially in vertical section and partially in end elevation, showing means for mounting a soap-tray between the mixing-valve and the back of the sink. Fig. 3 is a top-plan view of the sink, showing by full and dotted lines the swingable nature of the spout.

In the drawings, 2 represents generally a 25 well-known type of kitchen sink comprising the usual tray 2', the latter being provided with a waste outlet fitting 2", and an upright portion 2", which generally engage a wall, as 2". The back 2" is usually perforated, as at 2", for facilitating conducting 30 the supply of water from the adjacent wall to the forward side of the sink.

The water supply fixture includes a mixing-valve comprising an upright hollow cylindrical body 3, from which radiate in opposite directions hollow arms 3'-3", that communicate with the lower interior portion of the body. The remote ends of said arms may be threaded into hollow globular heads 40 4'-4", which respectively connect with the cold and hot water supply, by means of tail fittings or pipes 5-5', which pass rearwardly through the perforations 2" of the sink, and may connect in any suitable manner with the cold and hot water pipes, as 45 6-6' (see Fig. 3).

The tail pipes 5-5' are each provided with medial hexagon portions 5", for the use of a wrench, and their forward ends are 50 preferably fitted with gland nuts 5".

The water discharges into a globular part 8', from which it flows horizontally through a spout 8", to be discharged into the tray of the sink. The spout 8" may be rotated in the neck 3", for directing the stream of water 55 to different portions of the sink tray.

Soap trays as a rule are not included in the water supply fixtures for sinks, but as there is a growing demand for such facilities I have provided novel and simple means for 60 supporting a soap container, comprising an integral lug 18 which extends horizontally from the rear side of the body 3 (see Figs. 2 and 3). The free end of this lug is perforated to receive a vertically disposed rod 19, which may be held in the socket of the lug by gravity, and may therefore be readily applied or removed. The top-end of the rod 19 is formed with a rearwardly extended 65 perforated arm 19' upon which is mounted 70 an ordinary soap tray, as 20, the latter being detachably secured to said arm by a screw 20'. By this disposition and arrangement of the parts the tray 20 is positioned between the body 3 and the back 2" of the sink, with 75 in convenient reach of the user of the faucet, and does not in any way interfere with the the operation of the faucet. The lug 18 being disposed at the rear side of the body 3 does not disfigure nor interfere with the 80 ordinary handling of the fitting. In practice all of the bodies 3 are preferably formed with the lugs 18 for the optional use of the soap trays.

Having thus described my invention, what 85 I claim is—

1. The combination of a casing, hot and cold water supply pipes, valve means regulating the flow through said pipes, a handle for operating said valves means, and a soap holder mounted on the rear side of the casing and extending above the handle in back thereof.

2. In combination with a sink, a valve carrying casing connected to the sink to support the casing spaced from the back wall of the sink, a handle for operating the valve, a perforated lug carried by the casing and arranged in the space between the casing and the back wall of the sink, and a 100

soap carrier having a depending rod removably engaged in the perforation of the lug.

3. In combination with a sink, a valve carrying casing connected to the sink to support the casing spaced from the back wall of the sink, a handle for operating the valve,

a soap carrier, a rod depending from the carrier and secured thereto, and means carried by the casing to support the rod between the casing and the back wall of the sink. ¹⁰

In testimony whereof I affix my signature.

ORVIS W. VALLIER.
